UNITED STATES PATENT OFFICE.

JAMES L. MCQUARRIE, OF MONTCLAIR, NEW JERSEY, AND CHARLES L. GOODRUM, OF NEW YORK, N. Y., ASSIGNEES TO WESTERN ELECTRIC COMPANY, INCORPORATED, OF NEW YORK, N. Y., A CORPORATION OF NEW YORK.

MACHINE-SWITCHING TELEPHONE SYSTEM.

1,252,466.

Specification of Letters Patent.

Patented Jan. 8, 1918.

Application filed March 30, 1917. Serial No. 158,566.

To all whom it may concern:

Be it known that we, JAMES L. MCQUARRIE and CHARLES L. GOODRUM, citizens of the United States, residing at Montclair, in the county of Essex and State of New Jersey, and at New York, in the county of New York and State of New York, respectively, have invented certain new and useful Improvements in Machine-Switching Telephone Systems, of which the following is a full, clear, concise, and exact description.

This invention relates to machine switching telephone systems, and particularly to subscriber controlled systems of great capacity.

The object of the invention is to provide means whereby the capacity of the telephone system may be greatly increased without overtaxing the capacity of the subscribers in manipulating their impulse transmitters.

To increase the capacity of automatic telephone systems utilizing present day apparatus it is necessary to employ a greater number of digits in each telephone designation. This however leads to a psychological difficulty to overcome which a number of schemes have heretofore been devised. The present invention is a scheme which belongs to this class but which has features quite different from any other previously devised.

One feature of the present invention is a double dial sending device, each dial containing the regular ten finger holds and arranged upon actuation to send trains of impulses varying from one to ten. Around the break-points of one dial a resistance is connected, while around the break-points of the other dial there is no circuit.

The choice of the manipulation of one or the other of the dials is determined by the listing of the called line, the characters appearing on the two dials being different.

Another feature is the means for receiving the impulses and differentiating between those of different characters so as to properly control the action of a selector switch. This means consists of two relays, one responsive to weak currents, and the other responsive only to strong currents. The inter-
action of these relays, under control of the double dial sending device, actuates either one or another of two stepping magnets, one of which is adapted to take only half a step on its first energization, and thereafter a

full step upon each energization, and the other of which is adapted to take a full step upon each energization.

The manipulation of one dial causes one of these stepping magnets to be actuated, and the manipulation of the other dial causes the other of these magnets to be actuated.

Another feature of this invention is the manner in which the groups of terminals, to which the selector switch is directed, are periodically interspersed between one another.

The drawing represents a telephone system wherein a calling telephone line and a selector switch embodying the features of this invention are diagrammatically shown, and a line finder switch, a connector switch and a called telephone line are indicated.

DN and DL represent the two dials of the double dial calling device which are shown separately, but which may be combined in a single structure. The mechanical structure of the sending device, however, forms no part of the present invention. The dial DN operates break-points which entirely open the subscriber's line and the dial DL contains break-points which introduce a resistance R' into a subscriber's line.

Referring to the diagrammatical representation of the selector switch, LRW represents a relay responsive to weak currents, and LRS represents a relay responsive to strong currents only. These two relays are placed in series, and are controlled by the subscriber's line until the operations of the selector switch are completed.

Two stepping magnets PMN and PML drive the brushes B⁴, B⁵ and B⁶ in a vertical direction. The first actuation of the magnet PMN is adapted in any well-known manner—such for instance as is disclosed in Patent No. 1,161,837 issued to Bruce, November 30, 1915—to step the brushes one-half of a full step or a distance equal to the distance between two sets of terminals, such as T⁴, T⁵ and T⁶. Thereafter, each energization of the magnet PMN drives the brushes a full step or a distance equal to twice the distance between any two sets of terminals. All energizations of the magnet PML drive the brushes a full step or a distance equal to twice the distance between the sets of terminals.

The terminals are so arranged that the first, third, fifth and all odd numbered levels are reached by the actuation of the dial DN and the directed actuation of the magnet PMN. Periodically interspersed between these levels, that is, in the second, fourth and all even numbered levels, are terminals reached through the manipulation of the dial DL, and the directed actuation 5 of the magnet PML.

It is thought that the invention may best be understood through the following detailed description of the operation in setting up a connection between a calling and 10 called subscribers' lines.

Let it be assumed that the subscriber at the substation S removes his receiver from its hook. The well-known circuits employed in the line finder switch, indicated at LF, 15 cause the connection of the brushes B¹, B² and B³ to the terminals T¹, T², T³, whereupon the telephone line is extended to the first selector switch FS. A circuit is thereupon established from ground, battery, the 20 windings of relays LRS and LRW, the first position contact and side-switch wiper W¹, the brush B¹, terminal T¹, the contacts of the dial DN, the apparatus of the subscriber's substation S, the contacts of the dial 25 DL, the terminal T², the brush B², the side-switch wiper W² and its first position contact to ground. The relays LRS and LRW attract their armatures, whereby a circuit is established from ground, the armature 30 and alternate contact of relay LRS, the winding of slow release relay SR to battery and ground. The attraction of its armatures by the relay SR prepares circuits for either the magnet PMN or the magnet PML, and, at the same time, opens the 35 release trunk 1, leading to the line finder switch, and the release relay R² therein.

In order to illustrate the invention, two 40 actions on the part of the subscriber will be assumed, first, it will be assumed that he manipulates the dial DN to send the selector switch to an odd numbered level of terminals. When this action has been fully described it will be assumed that he manipulates the dial DL, this time to drive the 45 brushes of the first selector to an even numbered level of terminals.

The manipulation of the dial DN, as before stated, entirely opens the subscriber's 50 line, and is the well-known action of the present day automatic telephone dial switch. The interruptions in the line circuit cause the vibration of the armatures of both relays LRS and LRW. Upon the first retraction 55 of their armatures, a circuit is established from ground, the armature and normal contact of relay LRS, the armature and normal contact of relay LRW, the outer right-hand armature and alternate contact 60 of relay SR, the side-switch wiper W² and

its first position contact to a point where the circuit divides, extending in one direction, through the winding of magnet PMN to battery and ground, and in the other direction, through the left-hand winding of relay 70 2, to battery and ground. As in many other well-known systems, the relay 2 is slow to release, and, therefore, does not respond to the intermittent breakings of its energizing circuits. The magnet PMN, however, does respond to the interruptions, and 75 through the actuation of its armatures, drives the brushes B⁴, B⁵ and B⁶ to the desired level of terminals.

At the conclusion of this series of impulses the relay 2 slowly deenergizes, due to the attraction of the armatures of the relays LRS and LRW. The energization of relay 2 had established a circuit from ground, contact and armature of relay 2, 80 first position contact and side-switch wiper W⁴, the winding of magnet E to battery and ground. Upon the retraction of its armature by the relay 2, as just described, relay E becomes deenergized, and in retracting its armature escapes the side-switch wipers into their second position.

In the second position of the side switch a circuit is established from ground, the second position contact and side-switch wiper W⁵, the contact and armature of relay SM to battery and ground. Relay SM breaks its own circuit, and, through the consequent vibration of its armature, drives the brushes B⁴, B⁵ and B⁶ around and over the terminals 90 T⁴, T⁵ and T⁶ until an idle trunk is encountered. Such idle trunk is characterized by ground potential on the terminal T⁶, and the brush B⁶, upon encountering such a 95 grounded terminal, projects the ground potential over the brush B⁶, through the second position contact and side-switch wiper W⁴, through the winding of the escape magnet E to battery and ground. Escape magnet E thereupon becomes energized and escapes the side-switch wipers into their third 100 position. The seizure of the trunk, through the terminals T⁴ and T⁵, operates in the well-known manner to remove the ground potential from the terminal T⁶, thereby 105 characterizing the trunk as busy.

The connector switch, indicated at CS, is now driven under the control of the dial DN or the dial DL in a manner similar to the actuation of the first selector FS into 110 association with the line leading to the subscriber's substation S¹. The operation of testing and ringing is complete in any well-known manner, and the connection finally 115 established.

After a period of conversation, the subscribers hang their receivers on their hooks, whereupon a ground is placed on the terminal T⁶ in the manner well known in the art, which ground is thereupon connected 120 125 130

through brush B⁶ to the third position contact and side-switch wiper W⁶, to a point where the circuit divides, extending in one direction through off-normal contact ON¹,

- 5 the winding of first selector release magnet R³ to battery and ground, and in the other direction, through the left-hand armature and contact of relay SR, the release trunk 1, the line finder off-normal contact ON, the
- 10 winding of line finder release magnet R² to battery and ground. Both of these release magnets are energized, and, through their respective armatures and contacts, establish holding circuits which maintain
- 15 them energized until the line finder and first selector switches are fully restored to normal.

It will now be assumed that the subscriber, instead of manipulating the dial switch DN, 20 manipulates the dial switch DL. The circuit change, which takes place through interruptions of the circuit through dial DL, introduces a resistance R¹ in series with the line circuit. The current flowing through 25 the line now becomes weak, and relay LRS retracts its armature, but the relay LRW maintains its armature in an attracted position. The interruptions therefore project a ground potential from the armature and 30 normal contact of relay LRS, the armature and alternate contact of relay LRW, the contact and inner right hand armature of relay SR, the side-switch wiper W⁷ and its first position contact to a point where the 35 circuit divides, extending in one direction, through the winding of magnet PML, to battery and ground, and in the other direction, through right-hand winding of the slow release relay 2, to battery and ground.

40 Slow release relay 2 attracts its armature and thereby energizes the relay E. The actuation of the magnet PML drives brushes B⁴, B⁵ and B⁶ to the desired even numbered level of terminals. Thereafter, the action 45 is the same as has been described in connection with the manipulation of the dial DN.

What is claimed is:

1. In a telephone system, means for sending trains of impulses of one character and means for sending trains of impulses of another character, selector switches, sets of terminals therein, means responsive to trains of impulses of one character for setting said switches upon certain of said sets of terminals, and means responsive to trains of impulses of another character for setting said switches upon certain others of said sets of terminals.

2. In a telephone system, selector switches, fixed terminals therein divided into groups, the terminals of the several groups being periodically interspersed between each other, impulse transmitters arranged to send trains of impulses of one character, impulse transmitters arranged to send trains of impulses of a different character, means responsive to the impulses of one character for setting said switches on the terminals of one group, and means responsive to the impulses of a different character for setting said switches on the terminals of another group.

3. In a telephone system, directly controlled automatic switching mechanisms, circuits leading therefrom divided into groups, telephone lines, means for causing said switching mechanisms to extend said telephone lines to one group of said circuits, means for causing said switching mechanisms to extend said telephone lines to a different group of said circuits, subscriber-controlled means for sending trains of impulses of one character to actuate said first-mentioned means, and subscriber-controlled means for sending trains of impulses of a different character to actuate said second-mentioned means.

In witness whereof we hereunto subscribe our names this 27th day of March, A. D. 1917.

JAMES L. MCQUARRIE.
CHARLES L. GOODRUM.
